UNITED STATES PATENT OFFICE.

FREDERICK L. H. SIMS, OF SOUTHAMPTON, ONTARIO, CANADA.

HOUSEHOLD FURNITURE.

Application filed April 18, 1925. Serial No. 24,207.

This invention relates to household furniture which will provide satisfactory accommodation for sleeping or repose, particularly adapted for use in apartments or residences 5 where space is limited.

I have in mind, in the present invention, two main objects. First, to so relate two pieces of furniture that they may be used separately and independently of one another 10 or one concealed within the other in such a manner that the concealing member may be used as before and without presenting an abnormal appearance. Secondly, to so construct the pieces that the concealing member 15 may be made of minimum external dimensions. Further objects I have in mind will hereinafter appear.

One method of attaining my objects is by forming one of the pieces of furniture as a 20 receptacle or container and the other a closable bedstead, preferably built of metal, the container being formed with sufficient internal space to receive the closed bedstead when it is tilted on end and the bedstead member 25 so constructed that when closed it will be of the smallest practicable dimensions from front to rear so that when received on end in the container the height of the latter may be kept within reasonable limits. In 30 my co-pending application No. 21,438 filed April 7th, 1925, similar objects to the above are attained but in a converse method to that employed in this application which is intended to cover the modified constructions 35 necessitated by this reversal. The specific arrangement for concealing the bedstead is to close it to its compact form, run it along the floor to engage a journal carried by the container, and then tilt it into the latter.

40 The invention is illustrated in the accompanying drawings in which.

Fig. 1 is a side elevation of my improved bedstead in the extended position;

Fig. 2 a plan view of part of Fig. 1;

45 Fig. 3 a detail showing the bedstead in position for an invalid's use;

Fig. 4 a side elevation of the bedstead, partly extended and illustrating the movements of the parts to their extended positions;

Fig. 5 a longitudinal section of the closed bedstead showing its position relative to the container;

55 Fig. 6 a section of the bedstead and a modified type of container showing the position of the former when not in use;

Fig. 7 a sectional detail of a container showing the frame for supporting the bedstead;

Fig. 8 a plan view of the frame shown in 60 Figs. 6 and 7;

Fig. 9 a cross section of the same; and

Fig. 10 a perspective detail of the lock for the legs of the outer mattress frame section.

In the drawings like numerals of reference 65 indicate corresponding parts in the different figures.

In Figs. 5 and 6 of the drawings, two types of containers and their relationship to the closed bedstead are illustrated.

In Fig. 6 the container 1 is shown as the lower portion of a radio cabinet but it will be distinctly understood that the container may be formed as a different type of furniture such as a dresser or the like. The container is formed with an open bottom and has an opening 2 in the front, the opening may be closed by a door 3.

In Fig. 5 is shown a bedstead in its closed position. This bedstead while being maintained within trade requirements as to its height above the floor is of the smallest practicable length, from front to rear, in its closed position. My container is readily formed with an internal space sufficient to receive the closed bedstead, but it is not feasible to design the container with sufficient depth to permit the closed bedstead to be positioned therein when it is in its normal position.

The solution of the difficulty is therefore 90 to provide means for tilting or swinging the bedstead into the container so that the bedstead will be positioned upright in the container.

When the container is formed as a woman's dresser (Fig. 5), it is absolutely imperative that the height from the floor to the underside of the dresser drawers shall not exceed 32", otherwise the article will not sell. In this type of container the latter is provided with a fixed journal 4 which extends across the lower part of the opening 2 adjacent the floor and is adapted to be engaged by the bedstead, so that the latter may be tilted into the container as hereinafter more fully 100 described.

In the first mentioned type of container the height of the internal space is not important but this type of furniture is generally provided with legs extending well below the door and sides of the cabinet. To maintain 110 the natural appearance of this type of furni-

ture, the journal 4^a is carried on a swingable frame 5. The latter is pivoted on gudgeons 6 secured to opposite ends of the cabinet, the pivots being arranged so that the journal 5 will tend, by means of gravity, to hang below them. Double stops are provided for limiting the swing of the frame in either direction, the stop 7 being adapted to limit the downward movement of the journal and position 10 it relative to the floor for engagement with the bedstead so that the latter may be tilted to rest on the frame 5. The stop 7^a is adapted to limit the movement of the frame when the bedstead is carried thereon. The stop 7 is formed by an eccentric, suitably carried on a stationary part, so that it may be adjusted 15 to vary the position of the journal 4^a relative to the floor.

The bedstead.

20 The bedstead is illustrated in Figs. 1 to 6. Briefly the bedstead comprises a truck supporting a mattress frame formed of inner, outer and intermediate sections hinged together, the pivots of one pair of joints 25 extending into bearings in the ends of the sides of the truck. The hinged connections between the outer and intermediate sections are formed as stop joints whereby these sections, when the mattress frame is extended, 30 may teeter on the axes of the pivots. When so extended, as hereinafter fully described, the mattress device in addition to the said pivots, is supported by two pairs of supports 35 pivoted on the truck and a pair of supports pivoted at the outer end of an end section of the mattress frame adapted to engage the floor. Means are provided for swinging the supports to and from their mattress frame 40 supporting position whereby the mattress frame is supported at four points on each side when it is extended and of these supports only the pivots, on which two sections of the mattress frame teeter, are operative 45 when the device is closed, the only other support then being the cams hereinafter described. When the mattress frame is closed, the outer section occupies a substantially horizontal position, the inner section, which is 50 slightly longer than the outer section lies below the latter and is slightly inclined to the horizontal, and the intermediate section occupies a position inclined to the vertical, at one end of the truck. Means are also provided 55 for engagement with the journals 4 or 4^a so that the bedstead may be readily tilted into the container 1 and positively positioned therein. When the bedstead is tilted it rests on its rear end as hereinafter described. 60 20 is the truck constructed and braced in any suitable manner and preferably formed of angle iron. At its front and rear ends the truck is provided with and suitably supported by pairs of ground wheels 23 and 21, respectively. 65

On the truck is mounted a mattress frame formed in three sections 24, 25 and 26. The inner section 24 and the outer section 26 are formed of T-angle bars, preferably of similar cross section but the former is slightly longer than the outer section. The intermediate section 25 is shorter than the outer section and is preferably of malleable iron being formed at its middle of L-section and near its ends of T-section. The construction of this 70 mattress frame is hereinafter more specifically described. For the present it will be sufficient to say that the section 24 is pivotally connected with the intermediate section 25 by the pivots 27 and the intermediate sections 25 75 with the outer section 26 by the pivots 28. 80

The mattress frame is pivotally connected with the truck, preferably in alinement with and by means of the pivots 28, which are cast on the intermediate section for a purpose 85 which will hereinafter appear.

When the mattress frame is extended as shown in Fig. 1, the free end of the inner section 24 is supported by means of an arm 29 which is actuated as hereinafter described, 90 and has its ends pivotally connected both with the sides of the section and with an extension 20^a pivoted at 20^b on the truck 20. This extension is adapted to be swung up and down and carries a pair of ground wheels 20^c which are adapted to engage the floor when the bedstead is opened and also when closed and the bedstead tilted on the journal 4 as shown in Fig. 5. The mattress frame adjacent the pivots 27 is supported, when in the position shown in Fig. 1, by means of the toggles 30 pivotally connected both with the truck and with the mattress frame, preferably concentric with and by means of the pivots 27. These toggle supports, it will be noted, 95 when the bedstead is extended, reach a position in which their pivots are in alinement, and therefore they must be actuated, as hereinafter described, before the bedstead is closed, to cause them to break in the correct 100 direction. The outer end of the outer section 26 of the mattress frame is supported by means of the supports or legs 31 pivoted on the sides of the mattress frame section 105 and provided with ground wheels 69. 110

The supports 30 and the legs 31 are moved to their operative positions by a swinging head board which I shall now describe. It is desirable when the bedstead is to be closed that the legs should be simultaneously brought to an inoperative position, and I arrange to effect this through the operation of the movable head board, which is arranged also to serve as a mattress retaining device. The head board 32 is connected to a pair of bent arms 33 pivoted on the sides of the mattress frame, and preferably outside the flanges thereof to prevent wear on the sides of the mattress as hereinafter described. 120 These arms are pivotally connected to con- 125

necting bars 34 pivotally connected at 35 with bent levers 36 pivotally connected adjacent their lower ends to diagonal braces which support the inclined ends of the truck 5 and engage inside the ends of the front of the truck to economize space in width.

When the mattress frame is extended, the pivot points 35 occupy a position intermediate of the pivots 28 and the headboard as 10 shown. As long therefore as the movable headboard is retained in its upright position, the outer end of the section 26 of the mattress frame cannot be raised by tilting it on the intermediate section.

15 The connecting bars 34 are connected with the legs 31 by pivoted links 37. The upper ends of the legs extend above their pivots and a latch 38 is provided for each leg. These latches are pivotally carried by the mattress 20 frame and are provided with means adapted to engage over the upper end of the adjacent leg as shown particularly in Fig. 4. A bail 39 connects these latches 38 so that they may be simultaneously lifted to free the legs. The 25 engaging means are formed at one side by the turned in ends of the bail and at the other side by pins or projections 122 on the outer mattress frame section 16. From this it is 30 evident that the legs 31 will be locked in their supporting or operative positions when the head board 32 is swung up to the position shown in Fig. 1 and retained in this position by the latches 38 and projections 122. The latches are pivoted on plates 8 secured inside 35 the flanges of the mattress frame and these plates extend above the latter so that the latches 38 will rest in their locking position on the upper edge of the T-sectioned frame. The pivoted ends of the legs 31 lie against 40 the outside of the frame flanges so that they may be firmly held between the projections 122 and the latches 38 and the free ends of the legs are offset to clear the arms 33. This then permits the legs to swing inwardly and 45 upwardly as the headboard is swung to the position shown in Fig. 4. The connecting bars, it will also be seen, swing rearwardly, and the bent levers 36 and connecting bars are so proportioned that the pivotal points 50 35 between the levers and connecting bars are brought into alignment with the pivots 28 and when in this position and the device is closed, the connecting bars serve to hold the headboard as a mattress gripping device as 55 hereinafter referred to. The outer section of the mattress frame is now free to swing up. By the time the bent levers have reached the position just described, their lower ends 60 have come into engagement with the end members of the adjacent end of the truck frame so that the levers can swing no further. (See particularly Fig. 5.)

Pivotally connected with the toggle supports 30 are the connecting rods 41. The 65 other ends of these are slotted to engage pins

60 on the bent levers 36. When the parts are in the position shown in full lines in Fig. 1, the pins 60 are at the right hand ends of the slots, and the connecting rods are in position to hold the toggles extended as shown, 70 to support the mattress frame section 25. When the head board is swung to align the pivots 35 and 28, to close the device, the rods 41 are moved to the position indicated in dotted lines in Fig. 1 with the pin 60 in 75 engagement with the left hand end of the slot, which breaks the joint of the toggles 30. The swinging head board thus simultaneously actuates the legs 31 and the toggles 30 to their inoperative and operative positions 80 and they will engage the projections 122 in the latter position so that the latches 38 will lock these parts in this position.

To prevent the toggles 30 going past the position shown in Fig. 1, as might happen if 85 considerable weight were applied to the outer end of the mattress frame section 24, one section of the toggle is provided with a projection 43 adapted to engage a pin 44 on the adjacent section. (See Figs. 1, 4 and 5.)

90 From the construction described it follows that the movement of the head board hereinbefore referred to not only draws up the legs 31, but also permits of the collapsing of the toggle supports 30. (See Figs. 1 and 4.) 95 When the legs are brought to their inoperative position by the bringing of the movable headboard to its mattress engaging position, the outer section 26 is free to be raised at its outer end, the sections 26 and 25 of the mattress frame then teetering on its pivotal connections with the truck. As the outer mattress frame section is raised, the section 25 is 100 lowered.

105 During this movement the inner section 24 is moved downwardly and inwardly by the arms 29 from the position shown in Fig. 4. These arms are pivotally connected with brackets 10 secured to the flanges of the T-members which form the inner section, the axes of the pivots are substantially midway between the upper and lower edges of the T-members. The other ends of the arms are pivotally connected with the extension, the 110 axes of these pivots being offset relative to the horizontal center line of the extension. The latter is formed by two angle iron members each being pivoted at 20° to the adjacent side members of the truck 20. These members are connected by a transverse brace 20° which is located adjacent the pivots 20° and to the rear thereof when the extension is in its 115 operative position. The brace carries two cams 46 formed of channel iron, the free ends thereof being at a much greater distance from the pivots than the inner ends of the cams. With this arrangement the free ends of the cams, when the extension is lowered to rest on the floor, extend much higher above the latter than the ends of the cams adjacent the brace, 120 125 130

when the extension is raised off the floor. As the section 24 is being actuated downwardly and inwardly it contacts with and has a rolling action on the free ends of the cams 46 which serve to maintain the three pivotal connections, of one end of the arm 29 with the extension 20^a and the other end of the arm with the section 24 and the pivot 20^b, out of alignment whereby the extension will be readily swung to its raised position. The free ends of the cams, it will be noted, lie in front of the pivots 20^b so that the weight of the section 24 resting on the free ends has a tendency to rock the extension and raise its free end off the floor. As the extension is being raised by the closing movement of the section 24 the cams are rocked to lower the latter and also prevent it engaging and thus damaging the floor. As there is considerable space between the inner and outer sections when the bedstead is closed, the cams are designed to keep the free end of the inner section a further distance from the floor than its inner end and thus raise the center of gravity for a purpose hereinafter described.

In extending the device again the movements are reversed, the section 24 being rocked upward by the cams until the ground wheels 20^e engage the floor, the parts being proportioned to make this occur just at the time the arm 29 is at a proper angle to the horizontal to further elevate the inner section into alignment with the outer end intermediate sections when their stop joints lock and they have been teetered to a horizontal position.

As the outer section of the mattress frame, when the bedstead is being closed, is swung towards its final position, the shoulders at its joint with the intermediate section, herein-after described, are engaged so that the outer section will rock the sides of the intermediate section to a position past the vertical, the outer part of the mattress frame then lying substantially horizontal and over part of the section 24.

The free ends of the sections 24 and 26 are held spaced by means of the fixed end boards 47, which are secured, by any suitable means such as the arms 48, to the ends of their respective sections. It will be noted that the movable head board has retained its mattress-engaging position during the operation and holds its end of the mattress firmly against the mattress fabric supported by the outer mattress frame section 26 so that the mattress carried by the device folds properly as the bedstead is closed. This action of the movable head board is due to the fact that, as hereinbefore described, the bent levers 33 are restrained from any movement which would tend to release the head board from engagement by the engagement of the ends 40 of the levers 36 with the sides of the adjacent end of the truck frame, at all times after the

section of the mattress frame carrying the movable head board, when the device is being folded, attains a position in alignment with the inclined intermediate section 25 or beyond that position, since after that position is attained any movement of the head board to release its grip tends to further rock the bent levers 36, which is resisted by their engagement with the frame as stated above.

It is necessary to provide a transverse brace to take the strain of the springs employed as the mattress fabric support upon the mattress frame at or about the connection between the intermediate and inner sections of the mattress frame. For this purpose I provide the bail-shaped brace 53, preferably formed of a channel bar. The ends of this brace are pivotally connected at 54 to the sides of the mattress frame section 24 adjacent the pivots 27 in such a position that shoulders 55 formed on the ends will engage beneath the stems of the T-section bars to maintain the brace in the position shown in Fig. 5 when the mattress frame is extended for use. The position is such that when the section 24 of the mattress frame is tilted downwardly due to the operation of closing the bedstead, the brace will not swing to or past the vertical position as hereinafter fully described so that it is readily closed up to the position against the mattress frame as shown in Fig. 5.

To swing the brace upwardly as described, it is provided with arms 56, which, during the process of closing the mattress frame, are adapted to engage the inwardly extending bases of the angle bar side bottom members of the truck frame. The brace is thus held up, without swinging to or past the vertical position, as the sections of the mattress frame are closed, until the brace finally assumes the position shown in Fig. 5. With this arrangement spring means are not required to raise the brace.

While the general arrangement of the truck frame will be understood from the description hereinbefore given, yet certain parts of the forward end of the truck are of importance and this end must be designed to give great strength and rigidity. The end members 57 may be of any suitable construction though preferably they will be constructed and trussed substantially the same as that shown and described in my co-pending application hereinbefore mentioned. These members are braced by a cross bar 59 which is preferably a channel. On the forward side of this channel is hinged, by means of a stop joint, a T shaped handle 58. The stop joint is formed by a projection 62 carried on the stem of the handle behind the pivot and adapted to engage the channel bar 59 to limit the upward movement of the handle relative to the truck. The rear ends of the bottom side members of the truck are provided with

70

110

115

120

125

130

open bearings 20^a, preferably formed as U notches located at the rear of the pivots 20^b and adapted to engage the journals 4 or 4^a, when the truck wheels 21 and 23 are on the 5 floor, so that the truck may be tilted by means of the handle 58, into the container. This handle is so positioned that the operator will have a tendency to bend at the knees to grasp it and by straightening himself up he will 10 lift the bedstead with a lesser amount of exertion than if the arms were used to lift it.

It will be noted that the end 57 is inclined rearwardly so that the pivots 28 are positioned to the rear of the ground wheels 23 15 which prevents the truck tilting when the extended mattress is being teetered on the said pivots. To prevent the truck tilting adjacent the pivot 20^b I form a stop joint between the adjacent ends of the extension 20^a 20 and the truck so that the extension can swing only in one direction. This is accomplished by providing the lower side members of the truck with abutments 20^c, formed by a transverse brace located in front of the pivots 20^b, 25 adapted to be engaged by the adjacent ends of the side members of the extension. Any weight applied to the frame at the rear of the arms 29 will cause the end of the extension to jam against the abutments 20^c and thus prevent the section 24 teetering on the arms 29.

As hereinbefore mentioned the height from the floor to the underside of the drawer in the container shown in Fig. 5 must not be above a predetermined distance. This necessitates 35 the truck being shaped so that it may be tilted into the container with a minimum of clearance space. This is accomplished by forming the inclined end 57 as a chord of an arc concentric with the axis of the bearings 20^a. In 40 other words the distance from the axis of the said bearings to either extremity of the inclined end 57 is equal so that a truck of slightly shorter length relative to the height of the container may be tilted into the latter.

45 It will be noted that the construction of the truck with its inclined end 57 and the inclined inner section 24, when the bedstead is closed as hereinbefore mentioned and shown in Figs. 5 and 6, tends to shift the center of 50 gravity up towards the outer section 26 and rearwardly which facilitates the tilting of the bedstead into the container.

To ensure there being no compressional 55 stresses on the connecting bars 34, the legs 31 are slightly inclined forwardly and, in order to bring the weight on a leg exactly over its point of support on the floor, the pivot of its ground wheel is placed perpendicularly below its pivotal connection with the outer mattress frame section.

60 The operation of the device is as follows, assuming the parts to be in the position shown in Fig. 1. The first operation is to pull up on the bail 39 to release the latches 38 from engagement with the upper ends of the legs 31,

and to then push the movable head board to its mattress retaining position as shown in Fig. 6. This operation moves the supports 30 and 31 to their respective inoperative positions. The instant the legs are disengaged from the latches, the outer end of the outer section 26 of the mattress frame may be elevated. The sections 26 and 25 of the mattress frame teeter on the pivots 28 until the section 24 strikes the cams 46, which cams govern the further lowering of the section 24 in harmony with the movement of the arm 29 for raising the extension 20^a as hereinbefore described. By the reversal of the movements, the mattress frame is extended. When all the parts are extended and the movable head board raised, the latches 38 are re-engaged automatically by gravity with the upper ends of the legs 31 as hereinbefore described. The act of pulling up the head board also draws 85 the toggle supports 30 to their final mattress frame supporting position.

It should also be noted that the various links, levers and connecting parts are bent or offset as may be necessary to enable them to 90 clear one another as they are moved to effect the various operations.

The mattress frame.

I am further enabled to secure stop joints 95 between the outer and intermediate sections and hinge joints between the intermediate and inner sections of much greater strength than has been heretofore attained. Ordinary rivet joints will not last any length of time under 100 my teetering action. At the joints, it will be noted, the stems of the T-sections of the mattress frame sections 24 and 26, are cut away to make room for the pivots and that the shoulder 65 formed on the side of the intermediate mattress frame section and which is 105 adapted to engage the stem of the adjacent T-angle member of the outer section is sufficiently distant from the centre of the pivot to give it an effective bearing against the stem and thus make a strong joint when the sections are in alinement.

The flanges of the sides of the intermediate sections are also preferably cut away to form shoulders 66 which engage the stems of the 115 adjacent T-angle outer section when the bedstead is closed.

The side members of the intermediate section of the mattress frame are also preferably formed with a greater thickness of material 120 in the flange than the T-sections of which the other parts of the mattress frame are formed, thus further increasing the strength of the joints and giving the shoulders 65 and 66 a wide bearing on the stems of the adjacent T-sections. These shoulders are so spaced relative to one another that the sections when 125 extended will be in the horizontal plane and when closed the intermediate section will lie substantially in the same plane as the inclined 130

end 57 of the truck. In this intermediate section, the exact T-form is departed from, the T-form being found at the ends only, while the centre is of L-section. The two forms of 5 section merge into one another gradually, one leg of the L-section being integral with and also in alinement with the stems of the T-sections, the outer end of the L-section is deepened to maintain the stiffness and 10 strength of the design. To further stiffen the intermediate sections to prevent their twisting due to torsional stresses, I form ribs 62 arranged transversely of the L sectional portions of the sections.

15 When it is desired to incline the inner section 24 to form a back rest for an invalid, (as indicated in Fig. 3), the free end of this section is raised from its horizontal position, after the bedstead has been extended and supported in that position by the arms 29 and extension 20^a. These members form a toggle link and the horizontal legs of the extension angle irons are adapted to engage the arms to limit their movement in one direction and 20 thus act as a check after the center pivot has passed the centers of the other pivots.

Referring to Figs. 5 and 6 it will be noted that when the bedstead is tilted into a container, the ground wheels 20^a engage a support which may be the floor or the swingable frame 5. In either case the ground wheels 30 position the end of the truck away from the support which prevents damage to a floor when the latter acts as the support.

25 What I claim is:

1. In a bedstead, the combination of a truck having a frame extension hinged directly thereon and adapted to be moved into and out of engagement with the floor; a closable mattress frame formed with two sections hinged together, one section being pivotally supported on the truck and the other pivoted on the first section; and an arm pivotally connected with the said extension and with 40 one of the sections, the arm being adapted to support the last mentioned section when the second mentioned section is raised, and to swing the extension towards an upright position when the second mentioned section is lowered.

2. In a bedstead, the combination of a truck having a hinged extension adapted to be moved into and out of engagement with the floor; a closable mattress frame formed in sections hinged together, one section being pivotally supported on the truck; an arm pivotally connected with the said extension and with one of the sections, the arm being adapted to support the last mentioned section when the frame is extended; and means adapted to be engaged by the last mentioned section when it nears its closed position whereby the arm is maintained in a position to readily swing the extension upwardly off the floor.

65 3. In a bedstead, the combination of a truck

having a hinged extension adapted to be moved into and out of engagement with the floor; a closable mattress frame formed in sections hinged together, one section being pivotally supported on the truck; an arm pivotally connected with the said extension and with one of the sections, the arm being adapted to support the last mentioned section when the frame is extended; and means carried by the extension adapted to be engaged by the last mentioned section when it nears its closed position whereby the arm is maintained in a position to readily swing the extension upwardly off the floor, the said means being adapted to control the lowering of the section as the extension is being raised.

4. In a bedstead, the combination of a truck having a hinged extension adapted to be moved into and out of engagement with the floor; a closable mattress frame formed in sections hinged together, one section being pivotally supported on the truck; an arm pivotally connected with the said extension and with one of the sections, the arm being adapted to support the last mentioned section when the frame is extended; and means on which the last mentioned section rides when it is adjacent its closed position whereby the arm is maintained in a position to readily swing the extension upwardly or downwardly as the section is moved to its closed extended positions respectively.

5. In a bedstead, the combination of a truck having a hinged extension adapted to be moved into and out of engagement with the floor; a closable mattress frame formed in sections hinged together, one section being pivotally supported on the truck; an arm pivotally connected with the said extension and with one of the sections, the arm being adapted to support the last mentioned section when the frame is extended; and a cam carried by the extension for supporting the last mentioned section adjacent its closed position whereby the arm is maintained in a position to readily swing the extension upwardly or downwardly as the section is moved to its closed and extended positions respectively, the cam being adapted to raise the section as the extension is being lowered at the beginning of the movement for extending the bedstead.

6. In a bedstead, the combination of a truck having a hinged extension adapted to be moved into and out of engagement with the floor; a closable mattress frame formed in sections hinged together, one section being pivotally supported on the truck; an arm pivotally connected with the said extension and with one of the sections, the arm being adapted to support the last mentioned section when the frame is extended; and a cam carried by the extension for supporting the last mentioned section adjacent its closed position whereby the arm is maintained in a position

to readily swing the extension upwardly or downwardly as the section is moved to its closed and extended positions respectively, the cam being adapted to raise the section as 5 the extension is being lowered at the beginning of the movement for extending the bedstead and to control the lowering of the section as the extension is being raised.

7. In a bedstead, the combination of a truck 10 having a hinged extension adapted to be moved into and out of engagement with the floor; a mattress frame formed of inner, outer and intermediate sections hinged together and pivotally supported on said truck so that 15 the intermediate section may swing to a position below said pivots with the inner adjacent section lying at an angle thereto; and an arm pivotally connected with the inner section and the truck extension for supporting the said 20 section when the bedstead is extended, the hinged connection between the intermediate and outer sections being formed as a stop joint whereby the said sections will teeter on the pivot to move the inner section to close or 25 extend the bedstead and simultaneously raise or lower the said extension.

8. In a bedstead, the combination of a truck 30 having a hinged extension adapted to be moved into and out of engagement with the floor; a mattress frame formed of inner, outer and intermediate sections hinged together and pivotally supported on said truck so that the intermediate section may swing to a position below said pivots with the inner adjacent 35 section lying at an angle thereto; an arm pivotally connected with the inner section and the truck extension for supporting the said section when the bedstead is extended; and a cam carried by the extension for sup- 40 porting the inner section adjacent its closed position, the hinged connection between the intermediate and outer sections being formed as a stop joint whereby a movement of the outer section to extend the bedstead will cause 45 the inner section to lower the said extension and thus raise the inner section.

9. In a bedstead, the combination of a truck 50 having an extension pivotally mounted thereon adapted to be moved into and out of en- gagement with the floor; a closable mattress frame formed in sections hinged together, one section being pivotally supported on the truck; an arm pivotally connected with the 55 said extension and with one of the sections, the arm being adapted to support the last mentioned section when the frame is ex-

tended; and a cam secured to the extension for supporting the last mentioned section adja- 60 cent its closed position whereby the arm is maintained in a position to readily swing the extension upwardly off the floor, the outer end of the cam being positioned forward of the said pivot whereby the weight of the section contacting therewith will tend to raise 65 the extension.

10. In a bedstead, the combination of a truck 70 having a hinged extension adapted to be moved into and out of engagement with the floor; a mattress frame formed of inner, outer and intermediate sections hinged together and pivotally supported on said truck so that the intermediate section may swing to a position below said pivots with the inner adjacent section lying at an angle thereto; and an arm pivotally connected with the inner section and the truck extension adapted to normally support the said section in sub- 75 substantially the same plane as the other sections when the bedstead is extended, the extension and the arm being adapted to form a toggle 80 for supporting the inner section at an angle to the other sections.

11. In a bedstead, the combination of a truck 85 having a hinged extension adapted to be moved into and out of engagement with the floor; a mattress frame formed of inner, outer and intermediate sections hinged together and pivotally supported intermediate its ends on the said truck; a pair of supports adapted to support the intermediate section 90 from the truck; a pair of supports carried by the outer section for engaging the floor; and an arm adapted to support the inner section from the extension.

12. In a bedstead, the combination of a truck 95 having a lower side member provided with a bearing adjacent one end thereof by means of which the truck may be hinged on a fixed support; an end member fixedly se- 100 cured to the end of the side member remote from the bearing and inclined to the side member to form a chord of an arc concentric with the said bearing; and a sectional mat- 105 tress frame pivoted on said end members and closable to lie within a circle including the aforesaid arc whereby the bedstead may be swung on said bearing through a space no longer than the overall length of said side member.

Signed at Toronto, Canada, this thirty-first 110 day March, 1925.

FREDERICK L. H. SIMS.
